UNITED STATES PATENT OFFICE.

HERMAN EISELE, OF CLEVELAND, OHIO, ASSIGNOR TO WILLIAM DIEHL, OF CLEVELAND, OHIO.

DEVICE FOR REGULATING PRESSURE.

1,050,438.

Specification of Letters Patent.

Patented Jan. 14, 1913.

Application filed June 27, 1912. Serial No. 706,146.

To all whom it may concern:

Be it known that I, HERMAN EISELE, a citizen of the United States, residing at Cleveland, in the county of Cuyahoga and State of Ohio, have invented a new and useful Improvement in Devices for Regulating Pressure, of which the following is a specification, the principle of the invention being herein explained and the best mode in which 10 I have contemplated applying that principle, so as to distinguish it from other inventions.

My invention has general reference as already stated to a device for regulating pressure, while its more particular association is 15 with specific coöperating improvements.

The object of the invention consists in the provision of a device of this character especially adapted for use in conjunction with casks or barrels in which liquids should 20 remain stored under a uniform pressure.

The said invention consists of means which are hereinafter described and particularly pointed out in the claims.

The annexed drawing and the following 25 description set forth in detail certain means embodying my invention, the disclosed means, however, constituting but one of various mechanical forms in which the principle of my invention may be applied.

Referring now to the drawing, in which like reference characters consistently designate similar parts throughout: Figure I is a side elevation of a device embodying the features of my invention. Fig. II is a vertical 35 section of the same. Fig. III is an enlarged view of one detail as represented in Fig. II. Fig. IV is a similarly enlarged section of the detail shown in Fig. III taken on a transverse line.

The structure comprises in its entirety as seen in either Figs. I or II any suitable type of base 1 which supports a water-retainer 2. This retainer is preferably though not necessarily of elongated cylindrical shape and inclosed at the top with a screw-cap 3. This cap is shown provided with a centrally disposed opening 4, the purpose of which will be hereinafter apparent. The container is furthermore provided below with a screw-threaded inlet opening 5 in which any approved type of check-valve 6 may be seated. This valve comprises in turn the common type of disk 7 provided with a comparatively smaller centrally disposed opening 8 and a properly sized valve seat 9. Adapted

to communicate with the other end of the check-valve 6 and the source of pressure is a connecting pipe 10. A cut-off valve 11 is preferably interposed in advance of the check-valve as clearly indicated. The retainer 2 is further provided at its bottom on the other side with another screw-threaded opening 12 to which the faucet 13 is attached for the obvious purpose of permitting the drainage of the container when desired.

Interiorly the container 2 is provided near its upper end, as shown in Fig. II, with a tight partition 14 and this partition is provided upon the side opposite that on which the check-valve is located, with a comparatively small opening 15. This partition should be located as represented, some distance above the level of the water within the container. The partition 14 is moreover provided with another larger and screw-threaded opening 16 in which a mercury-tube 17 correspondingly screw-threaded at its upper end is adapted to be suspended. The upper end of this tube projects somewhat above the partition and is also provided with a screw-cap 18. This screw-cap is provided with an opening 19 through which a pipe 20 extends to a point near the bottom of the mercury-tube. The lowermost extremity of this pipe is closed by a laterally perforated cap 21, and as seen in Fig. II is normally submerged in the mercury. A set-screw 22 extending through the side of the screw-cap 18 is adapted to abut the pipe 20 whereby its adjustment with respect to the bottom of the tube may be effected as will be readily understood. The screw-cap 18 is likewise provided with another screw-threaded opening 23, the purpose of which will be presently manifested.

A pipe 24 passes through the opening 4 and being similarly screw-threaded at its lowermost extremity, is designed to find accommodation within the opening 23. The portion of this pipe 24 immediately above the retainer cap 3 is surrounded with any acceptable form of stuffing box 25. Supported above the pipe 24 either as an integral part of it as suggested, or through the medium of any other feasible mode is a separating chamber 26. This chamber is provided above with an opening 27 communicating with the atmosphere. The chamber 26 has attached to it interiorly a duct 28 of considerable length though of smaller cross-

sectional area than the pipe 24 down through which it projects to a point near the bottom of the mercury-tube. The duct 28 is flared at its uppermost extremity to comprise two curved sections 29 and 30 each conforming and tightly affixed to the curvature of different sides of the interior surface of the chamber 26. The section 29 forms a close mechanical fit with a portion of the lower surface of the chamber 26 while the section 30 projects more nearly upright and though extending entirely across the chamber laterally with respect to the direction of its projection, is spaced from and non-contiguous with the opposite lower surface of the chamber 26. As so formed the sections 29 and 30 constitute partitions forming an upwardly projecting cup-shaped pocket or funnel. The chamber 26 is also fashioned interiorly with a substantially horizontal partition 31 spaced a slight distance above the upper extremity of the section 30 as best seen in Fig. III. This partition 31 is then curved first upwardly and then downwardly at 32 to assume a substantially semi-circular form having its free extremity 33 projecting directly downward. The chamber 26 is still further provided interiorly with a baffle-plate 34 interposed between the curvature 32 and the section 30 though non-contiguous with both. This baffle-plate is preferably shaped as an inverse curve with the upper portion partially following the curvature 32 and the lower extremity extending down into the cup-shaped pocket to a point slightly below the upper extremity of the section 30. The upper surface of the baffle-plate 34 is moreover serrated.

Exteriorly the water-container 2 is provided with the common type of insert valves 36 and 37 spaced some distance from each other and connected with the usual graduated gage glass 38. Connected with this upper valve 37 is a pipe 39 and connected in turn with this pipe is a pressure gage 40. The purposes of this mechanism being common to the art, it requires no elaborate explanation.

The operation of my pressure regulating device may now be stated to be as follows: Assuming a given quantity of water and mercury inclosed respectively within the container 2 and tube 17, it will be noted in the first instance that directly the valve 11 is opened, the initial discharge of pressure will be mitigated to a marked degree during its discharge through the check-valve 6. Such gases as do issue forth through the check-valve in a still more or less violent gust will then necessarily have to bubble up through the water in order to find an exit. The water is intended to act as a cleansing agent in order that the gas passing through it may be purged of whatever impurities such as particles of froth which are known

to have a deleterious effect upon the properties of the element mercury. The opening 15 in the partition is located upon the side opposite the inlet opening 5 in order to lessen the likelihood of particles of water being drawn through it. After passing through the opening 15, the gases are obviously compelled to travel downwardly through the pipe 20 and hence necessarily exert upward a pressure upon the supply of mercury in which the discharge opening of this pipe is submerged. Inasmuch as the height of the column of mercury disposed above the cap 21 directly determines the degree of pressure which it will off-set, it becomes necessary to provide adjustment means, such for example as the simple expedient of a set-screw 22. Were it not necessary in actual practice to make allowances for the mishandling or hasty manipulation of a device of this character, the mercury-tube 17 might have direct communication with the atmosphere. It is therefore because a communication between the receptacle in which the liquid under pressure is being stored and a pressure regulating device of this type is likely to be established with undue suddenness by completely opening the valve 11 at one stroke, that the additional provision of a separating means has to be provided to preclude the projection therefrom, and resultant loss of globules of mercury. With the need for the prevention of such an improper manipulation in mind, I have provided a pipe 24 adapted to communicate with the upper part of the mercury-tube, and communicating in turn with the opening at the upper outer extremity of this pipe. I have provided a separating chamber 26. This chamber absolutely precludes the discharge into the atmosphere as waste, of any globules of mercury coincident with the discharge thereto of a measure of gas which contributed to bring about a surplus pressure. This measure of gas having been too suddenly discharged would unquestionably tend to separate and carry upwardly with it through the pipe 24 globules of mercury. Directing notice now to the interior construction of the separating chamber, it will be observed that the course of such globules of mercury as have been propelled upwardly will pass around between one side of the chamber and the section 30, will then either impinge against the under side of the substantially horizontal partition 31 or against the serrated upper surface of the baffle-plate 34, thereafter in either case, and in any event eventually, either fall at once by the action of gravity directly into the pocket or first pass around the curved portion 32 of this partition to similarly fall into such pocket. The gas itself in the meantime will have of course taken the direct line of least resistance and been dis-

charged out through the opening 27 into the atmosphere, and at the same time the globules of mercury, whose discharge from the chamber was effectually hindered, have been 5 returned again through the duct 28 to commingle with the original supply.

Having now fully described my invention, what I claim and desire to secure by Letters Patent is:

- 10 1. A device of the character described comprising the combination of a water-container, a pipe connecting said container with a source of pressure, a mercury tube communicating with the upper part of said container, a separating chamber connected with the upper part of said tube, a partition within said chamber, a duct communicating with the bottom of said chamber and with said tube, and provided on its upper end 15 with a flared portion forming in conjunction with said chamber a funnel within said chamber and a baffle plate interposed between said partition and funnel and intersecting the latter.
- 20 2. A device of the character described comprising the combination of a water-container, a pipe connecting said container with a source of pressure, a mercury-tube, a second pipe connecting the upper part of said container with the lower part of said tube, a separating chamber, a third pipe connecting the upper part of said tube with said chamber, a duct connecting the lower part of said tube with said chamber and extending 25 through said last mentioned pipe, and a baffle plate positioned within said chamber.
- 30 3. A device of the character described comprising the combination of a closed upright water-container having a lower inlet, a closed upright mercury-tube, a pipe connecting the upper part of said container with the lower part of said tube, an open separating chamber located above and connected with the upper part of said tube, a
- 35
- 40

duct projecting into the lower part of both 45 chamber and tube, the upper extremity of said duct being flared and contiguous to one side of said chamber and a baffle plate positioned within said chamber.

4. A device of the character described 50 comprising the combination of a closed upright water-container having a lower inlet, a check valve connected therewith, a closed upright mercury-tube, a pipe connecting the upper part of said container with the lower 55 part of said tube, an open separating chamber located above and connected with the upper part of said tube, a duct projecting into the lower part of both chamber and tube, the upper extremity of said duct being 60 flared and forming in conjunction with one side of said chamber a pocket, and a baffle plate positioned over said pocket.

5. A device of the character described, comprising the combination of a base, a 65 water container mounted thereon and provided with a lower inlet and an upper outlet, a check valve at said inlet, a pressure gage associated with said container, a mercury-tube supported within said container, 70 said mercury-tube being provided above with a pair of openings, one such opening being in communication with said container, a duct extending through the other of said openings and projecting from said container, a separator connected outside with said duct, said separator being provided 75 interiorly with a plurality of baffle plates confronting said outlet, and another duct projecting into both separator and tube, the 80 upper portion of said last mentioned duct inclosing the lower portion of one of said plates.

Signed by me, this 26th day of June, 1912.
HERMAN EISELE.
